(57) **CLAIM**

The ornamental design for a portable ultrasonic imaging device, as shown and described.

DESCRIPTION

FIG. 1 is a front perspective view of a portable ultrasonic imaging device, showing our new design;

FIG. 2 is a rear perspective view thereof;

FIG. 3 is a bottom plan view thereof;

FIG. 4 is a front elevation view thereof;

FIG. 5 is a top plan view thereof;

FIG. 6 is a right side elevation view thereof;

FIG. 7 is a left side elevation view thereof;

FIG. 8 is a rear elevation view thereof;

FIG. 9 is a front perspective view of the portable ultrasonic imaging device of FIGS. 1-8 in the open configuration and the side panel portion shown in the extended position; and,
FIG. 10 is another front perspective view of the portable ultrasonic imaging device of FIGS. 1-8 in the open configuration and the display screen portion shown in the vertical position.

The broken lines in the drawing views are included for the purpose of illustrating portions of the portable ultrasonic imaging device that form no part of the claimed design.
